HAIR CURLER

Robert Bacon, Brooklyn, N. Y.

Application February 15, 1949, Serial No. 76,513

4 Claims. (Cl. 132—38)

1

This invention relates to a hair curler, and more particularly to a hair-curling device for supporting curled strands of hair close on the scalp during the curling operation.

It is an object of this invention to provide a hair-curling implement of the kind to be more particularly described hereinafter, which is formed substantially in the manner of a pair of comb sections having interengaging teeth for securing a curl therebetween during the drying or curling steps of the curling procedure.

Another object of this invention is to provide a curling device of this kind which is formed in a novel manner to provide for the formation of the curl thereon in one position, and to engage on the upper and lower sides of the curl in the extended position for securing the curl while drying or forming.

Still another object of this invention is to provide a hair curler formed of a pair of interengaging comb members pivoted together in such a manner that the curl to be set will be substantially clamped between the interengaging teeth of the comb and the relation of the comb segments or sections is such that the curler, when spring pressed to extended position on the person whose hair is being curled, will not scratch or otherwise injure the person upon the sliding movement of the ends of the teeth in engagement with the scalp.

A further object of this invention is to provide a curler or clamp for holding a curl of hair in a set position, so constructed and arranged whereby the curl may be initially formed by coils about the curler and then clamped on the curler by the clamped engagement of the interengaging jaws or fingers. The curler is readily used by the operator with a minimum of effort and without the use of extraneous tools.

With the above and other objects in view, my invention consists in the arrangement, combination and details of construction disclosed in the drawings and specification, and then more particularly pointed out in the appended claims.

In the drawings:

Figure 1 is a side elevation of a pair of curlers constructed according to an embodiment of this invention, one of the curlers being shown in the extended position, and the other curler being shown in the retracted or curl-forming position;

Figure 2 is a bottom plan view of a curler, showing a lock of hair secured between the comb elements;

Figure 3 is a longitudinal section, taken on the line 3—3 of Figure 2, showing the curler in the partially-retracted position in dotted lines;

2

Figure 4 is a longitudinal section of the curler showing the relation of the elements thereof in the retracted position;

Figure 5 is a transverse section, taken on the line 5—5 of Figure 3;

Figure 6 is a top plan view of a modified form of curling device;

Figure 7 is a fragmentary longitudinal section, taken on the line 7—7 of Figure 6;

Figure 8 is a side elevation of a second modified form of this invention;

Figure 9 is a transverse section taken on the line 9—9 of Figure 8.

Referring to the drawings, the numeral 10 designates generally a hair-curling device constructed according to an embodiment of my invention to provide for the forming of a curl thereon and for securing and setting the curl in a selected position on the head of the person whose hair is being curled. The curler 10 is particularly designed for the ready manipulation by an operator, the function and operation of the curling device 10 being such that it may substantially be operated by one hand of a skilled operator.

The curler 10 is formed of a pair of handle elements 11 and 12 which are connected together for movement relative to each other. Each of the handle elements 11 and 12 consists of a bar 16 having an end portion 17 of arcuate configuration. The end portion 17 of the handle element 11 has a jaw or comb element 14 secured thereto while the end portion 17 of the handle element 12 has a like jaw or comb element 15 attached thereto. As shown in Figures 2 and 3, the bars 16 are arranged in inverse end to end relation, with the jaw or comb element 14 of the bar 16 of the handle element 11 extending over at least a portion of the bar 16 of the handle element 12 and coacting with the latter bar 16, and the jaw or comb element 15 of the bar 16 of the handle element 12 extending over at least a portion of the bar 16 of the handle element 11 and coacting with the bar 16 of the latter named element.

Means are provided connecting the bars 16 for movement relative to each other to a position in which the jaws 14 and 15 of the respective bars 16 are in an adjacent and confronting relationship and thereby form a mandrel for the winding of hair to be curled therearound, and for return movement from said position to the position in which the jaw 14 of the bar 16 of the handle element 11 extends over at least a portion of the bar 16 of the handle element 12 and the jaw 15 of the bar 16 of the handle element 12 extends over at least a portion of the bar 16

of the handle element 11 and thereby grippingly hold the curled hair therebetween to set the curl. Such means embodies a resilient element or section 19 which extends over adjacent ends of the bars 16 of the respective handle elements 11 and 12 and is seated in complementary recesses 18 formed in said adjacent ends of the bars. The resilient element of section 19 is preferably formed of rubber or other stretchable material and provides a pivot member for hingedly connecting the bars 16 for rocking movement relative to each other. The strip of rubber forming the resilient element of section 19 may be secured within the recesses 18 by glue or other fastening means.

The comb element 14, which is carried by the handle section or member 11, is formed with a back section 20 having forwardly-extending teeth 21 secured thereto, or preferably formed therewith. The back section 20 is adapted to underlie the arcuate end portion 17 of the handle section 11 to provide for the downward offset positioning of the teeth 21. The back section 20 is secured to the arcuate end portion 17 adjacent the resilient element 19, and the fingers or comb elements 21 are adapted to be extended forwardly beyond the resilient element 19 for overlying the adjacent arcuate end of the adjacent handle section 12. The handle section 12 is provided with a correlated comb section or element 15, having a back 22 and forwardly-extending teeth 24 carried thereby. The teeth 24 of the comb element 15 are adapted to extend between the teeth 21 of the comb element 14 and overlie the confronting adjacent section of the correlated handle element 11. The comb tooth or teeth 24 of the comb section 15 are downwardly offset from the handle section 12 in the same manner as the teeth 21 are downwardly offset from the handle section 11, described above. The back sections 20 and 22 of the comb elements 14 and 15, respectively, are adapted to be secured to the lower side of the handle sections 11 and 12 by cement or other suitable fastening means, and the teeth of the respective comb sections are adapted to be downwardly offset relative to the end portions 17 of the handle sections in the extended position of the curler. The downwardly-offset disposition of the teeth provides for the positioning of a lock of hair, after being curled, between the teeth and the adjacent portions of the bar 16 of the handle sections 11 and 12.

In the use and operation of the hair curler 10, the handle sections 11 and 12 are moved relative to each other in a position in which the jaws or comb elements 14 and 15 of the respective bars 16 are in an adjacent and confronting relationship, as clearly shown in Figures 1 and 4 of the drawings, with the fingers 21 and 24 extending downwardly from the resilient element 19, the jaws 14 and 15 and the fingers or teeth 21 and 24 forming a mandrel for the winding of hair to be curled therearound. The lower ends of the fingers 21 and 24 are spaced apart a slight distance, and the fingers of each of the comb sections are disposed for being positioned between the fingers of the confronting comb section. In the disposition of the curler 10 in the folded position, the resilient element 19 is adapted to be stretched between the abutting ends of the end portions 17. For initially forming the curl, the curl or lock of hair is initially engaged about the upper ends of the handle sections, or the bars 16. The curler 10 is then rotated in the fingers of the

operator for forming the curl thereabout. The lock of hair may be coiled about the handle sections of the curler 10 until the handle sections are substantially in engagement with the scalp of the customer. At this time the curl may be moved downwardly by sliding from the upper handle sections to a position about the lower ends of the fingers or teeth 21 and 24. From this position, the operator may remove his fingers from the handle sections or other portions of the curling device 10 and the resiliency of the resilient element 19 will press the handle sections 11 and 12 divergently apart to their longitudinally-aligned, extended position. Upon movement of the handle sections to their extended position, the teeth 21 and 24 will be disposed in interengaging relation to each other, so that the extreme ends of the teeth will overlie the back section of the other comb member. Upon movement of the curler 10 to its extended position, the teeth 21 and 24 will engage below the lowermost hairs of the curl for clamping the curl between the adjacent comb sections and between the comb sections and the outer surface of the handle arms 19.

In Figures 6 and 7, there is shown a modified form of this invention, in which the modification consists primarily of the hinged connection between the adjacent curler sections 31 and 32. The curler handle members 31 and 32 of the modified curler 30 are formed in substantially the same manner as the handle sections 11 and 12 of the form of the invention described above. Each of the handle sections 31 and 32 comprises an outwardly-extending, substantially horizontal arm 34 and 35 on the outer end thereof and an inner bowed section 36 and 37. One of the handle sections, as the section 31, is formed with forwardly-extending ears 38 on the opposite sides thereof which extend forwardly from the inner end of the inner handle section 36. The ears 38 are disposed along the side edges of the handle section 31 and are formed with transverse apertures therein whereby the ears 38 constitute hinge barrels for a hinge 40 which connects the handle sections 31 and 32 together. The confronting handle section 32 is formed with forwardly-extending ears 39 on the inner end of the arcuate portion 37, which are adapted to be disposed within the inner sides of the outer ears 38 of the confronting handle section 31. The ears 39 are formed with transverse openings therethrough for alignment with the openings of the ears 38 and a hingepin or pintle 41 is extended through the apertures of the ears 38 and 39.

A coiled spring 42 is coiled about the pintle 41 between the ears 39 of the handle section 32 and one end 44 of the spring 42 is adapted to be disposed on the upper surface of one of the handle sections, as the section 32. The other end 45 of the spring 40 is adapted to overlie the upper surface of the other handle section 31. The positioning of the spring 41 on the pintle 41 and its engagement with the handle sections 31 and 32 is such that the handle sections are continuously biased or spring pressed to their longitudinally-aligned, extended position.

Confronting, interengaging comb elements 46 and 47 are carried by the adjacent handle sections 31 and 32, respectively. The comb sections or segments 46 and 47 are formed substantially in the same manner as the comb sections 14 and 15, described above, having interengaging comb teeth or fingers 48 and 49 which are adapted to be

disposed in the same relation as the fingers 21 and 24, described above.

In Figures 8 and 9, there is shown a second modified form of this invention, wherein that portion of the curler which was set out as two sections in the forms of the invention described above, is constituted as a single element. The hair curler 50 is formed of an elongated resilient element or body of leather, rubber or other suitable material which is bowed along the length thereof. A pair of longitudinally-extending wires 52 are extended along the length of the bendable body 51 to provide for the resiliency of the body by which the body is normally spring pressed or otherwise biased or urged to an extended position. A flexible covering 54 is positioned about the body 51 along the length thereof, the covering 54 being made of fabric, a transparent plastic film, or other suitable material. A pair of comb elements 55 and 56 are secured to the opposite ends of the body 50. The comb elements 55 and 56 are substantially formed in the same manner as the comb sections or elements described above for the other forms of this invention. The comb elements 55 and 56 each is formed with a back portion 57 and 58, respectively, having confronting, interengaging comb teeth or fingers 59 and 60. The teeth 59 of the comb element 55 are adapted to be extended on opposite sides of the teeth 60 of the comb element 56 in such a manner that the teeth 59 and 60 substantially intersect each other at the mid-point of the comb body 51. The teeth 59 and 60 are disposed downwardly from the body of the curler 50 at their intersecting point in the extended position thereof.

The comb back sections 57 and 58 are secured to the body 51 by thread or cord wound about the body and the back sections. The cord or thread 61 will secure the comb segments to the body portion of the curler 50, although other fastening means may be used.

The use and operation of the curler 50 is the same as the use and operation of the curlers 10 and 30, described above. In the retracted position of the curler 50, the body 51 is bent along the length thereof substantially pivoting at the mid-point for disposing the comb sections 55 and 56 in overlying relation one to the other, being spaced apart by the folded body 51 therebetween. The lower ends of the teeth 59 and 60 will be spaced apart in the same manner as the teeth 21 and 24 described and shown for the form of the invention designated by the numeral 10, and specifically shown in Figure 4 of the drawings.

I do not mean to confine myself to the exact details of construction herein disclosed, but claim all variations falling within the purview of the appended claims.

I claim:

1. A hair curler comprising a pair of bars each having a jaw at one end thereof, said bars being arranged in inverse end to end relation with the jaw of each bar extending over at least a portion of the other bar and coacting with the latter, and means connecting said bars for movement relative to each other to a position in which the jaws of the respective bars are in adjacent and confronting relationship and thereby form a mandrel for the winding of hair to

be curled therearound, and for return movement from said position to the position in which the jaw of each bar extends over at least a portion of the other bar and thereby grippingly holds the curled hair therebetween to set the curl.

2. A hair curler comprising a pair of bars each having a jaw at one end, said bars being arranged in inverse end to end relation with the jaw of each bar extending over at least a portion of the other bar and coacting with the latter, and means rigidly connecting said bars for rocking movement relative to each other to a position in which the jaws of the respective bars are in an adjacent and confronting relationship and thereby form a mandrel for the winding of hair to be curled therearound, and for return movement from said position to the position in which the jaw of each bar extends over at least a portion of the other bar and thereby grippingly holds the curled hair therebetween to set the curl.

3. A hair curler comprising a pair of bars each having a jaw at one end thereof, said bars being arranged in inverse end to end relation with the jaw of each bar extending over at least a portion of the other bar and coacting with the latter, and means rigidly connecting said bars for rocking movement relative to each other to a position in which the jaws of the respective bars are in an adjacent and confronting relationship and thereby form a mandrel for the winding of hair to be curled therearound, and for return movement from said position to the position in which the jaw of each bar extends over at least a portion of the other bar and thereby grippingly holds the curled hair therebetween to set the curl.

4. A hair curler comprising a pair of bars each having a jaw at one end thereof, said bars being arranged in inverse end to end relation with the jaw of each bar extending over at least a portion of the other bar and coacting with the latter, and means hingedly connecting said bars for rocking movement relative to each other to a position in which the jaws of the respective bars are in an adjacent and confronting relationship and thereby form a mandrel for the winding of hair to be curled therearound, and for return movement from said position to the position in which the jaw of each bar extends over at least a portion of the other bar and thereby grippingly holds the curled hair therebetween to set the curl, said means embodying a pin extending transversely through the adjacent ends of said bars and a return spring circumscribed about said pin and operatively connected to said bars.
